[57] **CLAIM**

The ornamental design for the handle, as shown and described.

DESCRIPTION

FIG. 1 is a perspective view of the handle constituting our new design, a shank being shown in phantom and not forming part of the claimed invention;

FIG. 2 is an end view of one end thereof;

FIG. 3 is an end view of the other end thereof;

FIG. 4 is a top plan view thereof;

FIG. 5 is a side elevational view of one side thereof, the other side being identical;

FIG. 6 is a bottom plan view thereof;

FIG. 7 is an end view of one end thereof of a second embodiment of the claimed invention;

FIG. 8 is an end view of the other end thereof;

FIG. 9 is a top plan view thereof;

FIG. 10 is a side elevational view of one side thereof, the other side being identical; and,

FIG. 11 is a bottom plan view thereof.
